INVENTOR

Robert Coyle,
BY
Chester L. Bradford,
ATTORNEY.

UNITED STATES PATENT OFFICE.

ROBERT COYLE, OF INDIANAPOLIS, INDIANA, ASSIGNOR TO ELIAS C. ATKINS, OF SAME PLACE.

ROTARY PLOW.

SPECIFICATION forming part of Letters Patent No. 612,827, dated October 25, 1898.

Application filed August 10, 1897. Serial No. 647,671. (No model.)

To all whom it may concern:

Be it known that I, ROBERT COYLE, a citizen of the United States, residing at Indianapolis, in the county of Marion and State of Indiana, have invented certain new and useful Improvements in Rotary Plows, of which the following is a specification.

The object of my said invention is to provide means whereby the operator may easily shift the position of the "land" carrier-wheel relatively to the other plow parts; and it consists in the combination and arrangement of devices hereinafter described and claimed.

Referring to the accompanying drawings, which are made a part hereof and on which similar letters of reference indicate similar parts, Figure 1 is a top or plan view of a rotary plow embodying my present invention; Fig. 2, a view of the central portion thereof, on an enlarged scale, as seen from the dotted line 2 2 in Fig. 1; and Fig. 3, a detail rear elevation as seen from the dotted line 3 3 in Fig. 2.

In said drawings the portions marked A represent the main frame part of the plow; B, the axle; C, the staggered "furrow" carrier-wheel; D, the land carrier-wheel; E, an arm on which said wheel is mounted, and F a screw-shaft by which the arm carrying it is operated.

The frame A is preferably of a form similar to that shown in Letters Patent No. 543,118, granted Atkins and Roberts July 23, 1895, and carries an arm A³ and the plows A' and A², as well as the various other parts of the plow mechanism.

The shaft B is secured to the frame A and to an arm A³ thereon. It is bent at a central point, so that one end is in advance of the other, as indicated in Fig. 1. Strongly secured to the outer end thereof is a bracket B'. Said bracket is also preferably secured to the arm A³ on the frame A.

The staggered furrow or guide carrier-wheel C is of a usual form. The construction shown is that wherein this wheel is adapted to be raised and lowered in operation, so as to run either in the bottom of a furrow or on the level surface, as may be desired, and includes a slide, which carries its spindle, and a rack

and lever for operating the same. It is shown in its raised position, as when positioned to run on the same level as the land carrier-wheel D. Said land carrier-wheel is also of a usual and well-known construction and is mounted on its spindle D', which is carried from the arm E. Said wheel D has a long hub d, with a suitable bearing-face, which bears against a similar face on said arm, as indicated in Fig. 1.

The arm E is pivoted on the shaft B and carries the spindle D'. It extends beyond said shaft B and develops into a screw-gear segment E', as shown most plainly in Fig. 2.

The shaft F is mounted in a long sleeve-like bearing in the bracket B' and carries the worm f on its end, which engages with and is adapted to operate the segment E' on the end of the arm E. It is provided at the upper end with the hand-wheel F', by which it may be conveniently operated and which is located near the driver's seat S.

By means of this construction and arrangement it is possible for the driver to easily cause the land carrier-wheel D to occupy such position relative to the other parts of the plow as may be desired and without dismounting and to accurately adjust said parts in relation to each other, while they will remain in adjusted position without other means of retention than the natural friction of the parts, all as will be readily understood.

Having thus fully described my said invention, what I claim as new, and desire to secure by Letters Patent, is—

1. In a rotary plow, the combination, of the frame, the plows carried thereby, the axle, the carrier-wheels, an arm E formed with a hub or bearing between its ends and mounted by means thereof to rock on the end of said shaft and carrying a spindle on one end on which the land carrier-wheel is mounted and having a segmental rack formed on its other end with which a worm on an operating-shaft F engages, and said operating-shaft F mounted in a suitable supporting-bracket, whereby said land carrier-wheel may be manipulated to raise and lower the plow-frame, independently of the wheel on the opposite side of the frame, substantially as set forth.

2. The combination, in a rotary plow, of the frame having the arm A³, the bent axle B, the bracket B' on the end thereof, the arm E pivoted on the end of said axle and having a segment on one end and a bearing for the carrier-wheel spindle on the other, said spindle, the carrier-wheel mounted thereon, and the screw-shaft F mounted in said bracket and having the worm f which engages with said

segment, the whole being arranged and operating substantially as shown and described. 10

In witness whereof I have hereunto set my hand and seal, at Indianapolis, Indiana, this 6th day of August, A. D. 1897.

ROBERT COYLE. [L. S.]
